(57) CLAIM

The ornamental design for a headphone assembly, as shown and described.

DESCRIPTION

Portions of the disclosure of this patent document contain material that is subject to copyright protection. The copyright owner has no objection to the facsimile reproduction by anyone of the patent document or the patent disclosure as it appears in the Patent and Trademark Office file or records, but otherwise reserves all copyright rights whatsoever.

FIG. 1 is a perspective view of a headphone assembly showing my new design, the opposite side is a mirror image.

FIG. 2 is a left side view thereof.

FIG. 3 is a right side view thereof.

FIG. 4 is a top view thereof.

FIG. 5 is a bottom view thereof.

FIG. 6 is a rear view thereof; and,

FIG. 7 is a front view thereof.

Portions of the drawings shown in dashed line are for illustrative purposes only, and form no part of the claimed design.
